UNITED STATES PATENT OFFICE.

MATHIAS R. KONDOLE, OF CYNWYD, PENNSYLVANIA, ASSIGNOR TO BOXBOARD PRODUCTS COMPANY, OF PHILADELPHIA, PENNSYLVANIA, A CORPORATION OF DELAWARE.

ART OF PACKING.

Application filed October 17, 1924. Serial No. 744,193.

My invention is particularly applicable to the packing of fruits or vegetables having round or curved shapes, such as apples, oranges, peaches and the like, and it is primarily designed to permit the packing of such articles or other objects so as to form a top or display layer of desirable appearance and of uniform character, with the apexes of the constituent articles of such display layer in a symmetrical or regular plane, with avoidance of the uneven appearance and vacant spaces ordinarily resulting from the topping of a pack built up from the bottom, particularly where tapered containers are used.

In accordance with my improvements, the display layer is first formed upon a surface having the contour desired for such display layer and upon this layer the pack is built, preferably in layers of decreasing area and housed between walls of a suitable temporary retainer having an open end for the insertion of the articles forming the pack. When a pack of suitable depth has been formed, a container conforming with the size and shape of the pack is telescoped over the retainer, the container having a closed end covering the open end of the retainer and an opposite open end or mouth for the display of the pack upon the inversion thereof. The pack is preferably built upon the bed of a rocking cradle having hinged members whereby the container may be clamped to the base during inversion and which form a housing holding the container walls against bulging or distortion by the weight of the pack until the closure and its fasteners are positioned to counteract the deforming pressure of the load.

The accompanying drawings are illustrative of my invention; Fig. 1 showing a transverse sectional view of apparatus for packing fruit in accordance with my improvements; Fig. 2 showing a side elevation of the same; Fig. 3 showing a plan view thereof, and Fig. 4 showing a packed container with the cover broken away and diagrammatically illustrating the alignment of the packed fruit.

In the drawings, there is shown a cradle comprising a base 1 supported on rockers 2 and having mounted thereon a bed 3 provided with a curved upper surface 4. A rim 5 is fixed to the periphery of the base 1 and

spaced from the beveled periphery of the bed 3 to form a channel 6 registering with a slot 7 in the base 1 for the reception of plates 8 and a hoop 9. The plates 8 have beveled ends and are held by the hoop and bed in position to form an open ended retainer having inclined walls converging toward the end opposite the bed 3.

Fruit or other pomiform articles may be laid in a uniform layer upon the concave surface 4 between the retaining walls 8 and the pack built up by the addition of further layers until the desired depth is attained, approximating the height of the walls 8.

A container 10, comprising a bottom 10^a with walls 10^b diverging therefrom to the open mouth 10^c, is telescoped over the pack and retainer walls 8 when the space between such walls has been filled.

The container is secured in position over the pack by a housing comprising a curved block 11 hinged to the base 1 and having an inclined bearing 11^a adapted for engagement with a container wall 10^b; an open frame 12 hinged to the block 11 and having thereon rockers 12' and a bearing 12^a engaging the container bottom 10^a; and blocks 13 hinged to the frame 12 and having bearings 13^a engaging a container wall 10^b. A hook 14 is pivotally connected to each end of the block 11 and latches over a stud 15 on the respective blocks 13, the hooks having offset bearing members adapted for engaging the ends of the container 10. Each block 13 also has hinged thereto a link 16 which is adapted to pass through slots 17 in the base 1 and has pivoted thereon a handle 18 provided with a lug 19 by which the clamp may be drawn up and fastened.

When the pack has been built up and the container 10 secured in place by the clamping means described, the cradle is rocked upon the rockers 2 and block 11 in the direction indicated by the arrow and seated upon the members 12'. The links 16 are then unfastened and the base 1 thrown back, the container walls being still held against bulging by the blocks 11^a and 13^a and the hooks 14. The plates 8 may then be withdrawn from between the container and its contents, and a flanged cover 10' secured over the container mouth 10^c by fasteners 10^d which engage the side walls of the container and are drawn transversely by keepers

10° so as to counteract the bulging effect on the container walls of the pressure of the load. When the fasteners have been secured in place, the hooks 14 are disengaged 5 from the studs 15 to free the container, which is then ready for shipment.

It will thus be seen that the layer first positioned in the pack and having the apexes of its constituent articles in a regular or 10 symmetrical plane of any desired contour becomes the top or display layer of the pack when the container is opened by removing the closure 10^a. In order to prevent excessive settling of the packed fruit, it is desirable that the plane of the bed surface 4 15 be such as to arch the layers of the pack so that the weight or vertical pressure of the pack is partially resolved into horizontal or diagonal thrust against the container walls which is taken up by the closure fasteners, which form tension members hooked 20 into the container walls. Such arching is not, however, essential if care be exercised in packing.

25 Ordinarily the hoop 9 is quite sufficient to keep the plates 8 in position, but if such hoop should at any time prove insufficient to support the walls 8 against the pressure of the pack during the packing operation, 30 the clamp members 11, 12, 13, 14 and 16 may be so latched during such operation as to confine the plates 8 in their proper places and the fruit inserted through the open

frame 12. The completed pack, if undisturbed, is virtually self supporting, hence 35 the clamping members may be released while the container is telescoped on the pack, and again fastened to hold the container against the base during the inversion thereof and the application of the cover and fasteners. 40

Having described my invention, I claim:—

1. The improvement in the art of packing which comprises a rocking base having a retainer seat, a curved block hinged to 45 said base, a link hinged to said block, a block hinged to said link, and means for detachably connecting said last named block and base together.

2. The improvement in the art of packing 50 which comprises a rocking base having a retainer seat, clamping blocks on opposite sides of said seat, and latching means for securing said blocks in position.

3. The improvement in the art of packing 55 which comprises a rocking base, a retainer having separable walls fixed to said base and adapted to have a container telescoped thereover, and means for clamping said container and base together and forming a rocker for rolling the apparatus to inverted position.

In testimony whereof I have hereunto set my name this 16th day of October, 1924.

MATHIAS R. KONDOLF.
